UNITED STATES PATENT OFFICE.

DAVID MCGUIRE, OF NORTHAMPTON, MASSACHUSETTS.

IMPROVEMENT IN MACHINES FOR CUTTING SCREWS.

Specification forming part of Letters Patent No. 140,212, dated June 24, 1873; application filed March 26, 1873.

To all whom it may concern:

Be it known that I, DAVID MCGUIRE, of Northampton, in the county of Hampshire and State of Massachusetts, have invented certain Improvements in Machines for Cutting Screw-Threads on Bolts; of which the following is a specification, reference being had to the accompanying drawings, in which—

Figure 1 represents a horizontal section of a die-stock and its connection with the mandrel, having my improvements applied thereto. Fig. 2 represents an end view of the inner end of the die-stock, detached from the mandrel; and Fig. 3 a similar view of the corresponding end of the mandrel.

My improvement relates to a new and improved mode of constructing and connecting the collet of the die-stock with the mandrel, with a view of facilitating the removal and replacement of interchangeable dies for cutting screw-threads on bolts, &c.

To enable others skilled in the art to make, construct, and use my invention, I will now proceed to describe its parts in detail, omitting a description of such parts of the machine as are unnecessary to a complete understanding of the present improvement.

In this case the drawings simply represent a portion or section of the mandrel of the machine, and of the die-stock and dies, and not of the operative parts of the machine proper, as such are not necessary; the improvement being capable of being applied to the mandrel of any machine used in cutting screw-threads on bolts, so far as known.

A represents the mandrel, and B an enlargement at its end to act as a socket, C, for the collet D of the die-stock E. At the inner end of the socket C are found two or more depressions *a* for the reception of the projections *b* formed on the end of the collet D. These depressions *a* and projections *b* are made of corresponding size and shape to act as teeth entering their sockets, and so as to fit easily but snugly within each other. Instead of using two or more of these teeth, *b*, but one of suitable size may be used, in which case, of

course, but one socket, *a*, would be necessary for its reception.

Through the side of the enlargement B of the mandrel is passed a thumb-screw, F, the inner end of which is made to enter a depression, *c*, formed on the outer periphery of the collet D, as seen in Fig. 1.

The depression *c* may be either a simple depression of suitable size and shape to receive the end of the thumb-screw, or it may be formed by cutting an annular depression around the collet, as shown in Fig. 1.

The die G is secured to the die-stock, by means of stout screws, *d*, in any suitable manner.

Thus constructed the die-stock is easily fitted to and removed from the mandrel, and when once fitted in and the thumb-screw tightened up, it forms a solid connection with the mandrel. These advantages are of great value where screw-bolts of different sizes have to be cut through the medium of interchangeable dies, or where dies of different sizes have to be used in cutting threads on bolts.

Having described my invention, what I claim as new, and desire to secure by Letters Patent, is—

1. A die-stock provided with a collet, D, having one or more clutch-projections, *b*, in combination with a mandrel provided with a corresponding socket, C, and one or more clutch depressions, *a*, the whole being constructed and operated in the manner substantially as and for the purposes set forth.

2. In combination with a die-stock having a collet, D, provided with clutch projections *b*, and a mandrel having a socket, C, and clutch depressions *d*, the thumb-screw F and depression *c*, as arranged for the purpose set forth.

In testimony whereof I have hereunto subscribed this specification.

DAVID MCGUIRE.
